UNITED STATES PATENT OFFICE.

EDWARD A. GEOGHEGAN, OF SAN FRANCISCO, CALIFORNIA.

SUPERHEATER.

1,309,025.

Specification of Letters Patent.

Patented July 8, 1919.

Application filed April 4, 1918. Serial No. 226,640.

To all whom it may concern:

Be it known that I, EDWARD A. GEOGHEGAN, a citizen of the United States, residing at San Francisco, in the county of San Francisco and State of California, have invented certain new and useful Improvements in Superheaters, and I do hereby declare the following to be a full, clear, and exact description of the invention, such as will enable others skilled in the art to which it appertains to make and use the same, reference being had to the accompanying drawings, and to the letters of reference marked thereon, forming part of this specification.

15 My invention relates to steam superheating apparatus, and the objects thereof are to so construct and arrange the several parts of the apparatus as to prevent stratification of steam as it passes through the apparatus, so that those particles of steam which contact with the inner surface of the several tubular passages from which they absorb heat will be caused to intermingle with those particles of steam which have not 20 come into contact therewith, so that instead of there being continuous annular strata of steam, the outer of which are dry, and the inner of which carry entrained moisture, passing through the apparatus, such strata 25 are broken up and the particles of steam have imparted to them a whirling or smoke-ring movement as they travel through the apparatus, thus insuring the contacting of every particle of steam with the inner 30 surface of the superheating tubes, so that all 35 possibility of a central core of steam heavily loaded with moisture will be eliminated.

The features of my invention are herein-after more particularly described and 40 pointed out, and are illustrated in the accompanying drawings in which:

Figure 1, is a vertical central section of a portion of a steam boiler with my improved superheating apparatus installed therein.

45 Fig. 2, is a plan view of my improved apparatus, having portions thereof broken away, removed from the boiler.

Fig. 3, is a front end view thereof.

In these drawings A indicates a steam 50 boiler having fire tubes A' adapted to receive return-bend superheater tubes B. I have shown a two stage superheater, that is, one with a series of pairs of return-bend tubes B'. The open ends of these return-bend tubes B' are connected with small

headers C which are provided with transverse walls which divide the interior of each header C into chambers c, c', c² and c³. The upper arm of the first return-bend tube B communicates with the chamber c, and the lower arm thereof communicates with the chamber c', while the upper arm of the lower return-bend tube B' communicates with the chamber c² and the lower arm of said return-bend tube B' communicates with the chamber c³. The chambers c' and c² are connected by means of return bend tubes C'. D indicates a transverse tubular intake header, which is connected with the small headers C by means of return bend tubes E 70 which enter the upper chambers c thereof, while the lower chambers c³ of said headers C are connected with a transverse tubular header F by means of curved tubes F'.

The several headers C, D and F, and curved tubes E, C' and F', are preferably located in the smoke-box G of the boiler A, where they are subject to heat, so that all of the tubular passages of the apparatus act upon the steam during its passage therethrough.

In operation steam is introduced into the intake header D from where it passes through the curved tubes E to the upper chamber c of the headers C, and thence through the upper bank of return-bend tubes B to the chambers c' in the headers C; thence through the bank of return-bend tubes C' to the chambers c² in the headers C; thence through the next bank of return-bend tubes B' to the lower chambers c³ of the headers C, from whence the steam passes through the bank of curved tubes F' to the outlet header F. During the flow of steam through the curved tubes E, C' and F', by reason of the inner and outer radii of the tubular passages therethrough, the columns of steam assume a whirling motion, the particles of steam rotating upon traveling axes, so that all stratification, or parallel lines are broken up, and the same is true in 95 regard to the looped ends of the tubes B'.

Having thus fully shown and described my invention so as to enable others to utilize the same, what I claim as new and desire to secure by Letters Patent is:—

In an apparatus of the class described, a series of vertical headers, the interiors of which are divided into separate chambers, a return-bend superheater tube connecting the first chamber with the second chamber, a

looped tube connecting the second and third chambers, a return-bend superheater tube connecting the third and fourth chambers, a horizontal inlet header, a tube connecting 5 said inlet header with the first chamber in said vertical header, a horizontal outlet header, and a tube connecting the fourth

chamber in said vertical header with said outlet header, substantially as set forth.

In testimony whereof I affix my signature. 10

EDWARD A. GEOGHEGAN.
